[57] **CLAIM**

The ornamental design for a video camera tripod, as shown and described.

DESCRIPTION

FIG. 1 is a front right perspective view of a video camera tripod showing my new design with the tripod legs fully extended and deployed;

FIG. 2 is an enlarged right side elevational view thereof;

FIG. 3 is a front elevational view thereof;

FIG. 4 is a top plan view thereof;

FIG. 5 is a left side elevational view thereof;

FIG. 6 is a rear elevational view thereof; and,

FIG. 7 is a bottom plan view thereof.

Legs of the tripod in FIGS. 2-7 are shown fragmentarily for ease of illustration.
